EBERHARD FLUES, OF FORT WASHINGTON, PENNSYLVANIA.

Design No. 3,988 dated April 26, 1870.

DESIGN FOR A SHAWL-MANTLE.

The Schedule referred to in these Letters Patent and making part of the same.

To all whom it may concern:

Be it known that I, EBERHARD FLUES, of Fort Washington, in the county of Montgomery and State of Pennsylvania, have invented and produced a new and original Design for Ladies' Outer Garments, which I style "La Russe." The following is a specification of the same.

The nature of my design is fully represented in the accompanying drawings, to which reference is made, and in which—

Figures 2 and 3, views of the body and collar-pieces before putting the garment together.

The garment which is the subject of this design, is intended to be worn like a mantle, over the shoulders of the person. It is formed of a long strip or piece, having its opposite sides parallel, and with a portion cut out at its top edge in the center, as at a. Said body is then drawn together at its middle to give to it the set or configuration shown in fig. 1, and to form loose folds or plaits b, which are bound at their tops by a band, c, and the side edges of the cut-out portion united or seamed together, as at d.

The garment has a collar, B, of the shape represented. Said garment may be fringed or ornamented at its edges, and cords or other fastenings attached to secure it around the neck of the wearer.

I claim the design for a ladies' outer garment, as shown.

EBERHARD FLUES.
